Primary Examiner — Susan Bennett Hattan*Assistant Examiner* — Janice Hallmark(74) *Attorney, Agent, or Firm* — Foley & Lardner LLP(57) **CLAIM**

We claim the ornamental design for a multi-function tool, as shown and described.

DESCRIPTION

FIG. 1 is a front top perspective view of a multi-function tool.

FIG. 2 is a front view thereof.

FIG. 3 is a rear view thereof.

FIG. 4 is a right side view thereof.

FIG. 5 is a left side view thereof.

FIG. 6 is a top view thereof; and,

FIG. 7 is a bottom view thereof.

The broken lines in the drawings depict environmental subject matter and are for illustrative purposes only and form no part of the claimed design.

1 Claim, 5 Drawing Sheets(56)
